Coupling devices for detachably coupling the ends of a ski binding cable, which is split behind the heel of the boot, are known, in which the coupling members are separated from each other in response to an excessive tension acting on the cable in the longitudinal direction of the ski so that the foot is released in the case of a frontal fall of the skier. In the case of torsional falls, in which the leg of the skier is subjected to torsion, and in the case of other lateral stresses, these known coupling devices release the leg only if a sufficiently strong component of force in the longitudinal direction of the ski is produced by the torsional or lateral force. It is an object of the invention to provide a coupling device which releases the foot in the case of a lateral movement of the skiing boot, i.e., in the case of twisting falls, and otherwise reliably connects the cable ends when the binding is applied. In a development of the invention, the coupling device is to be designed in such a manner that it releases the foot in the case of twisting and frontal falls.

In a coupling device for detachably connecting the ends of a ski binding cable which is split behind the heel of the boot, this object is accomplished according to the invention in that a yoke conforming to the curvature of the heel is bisected behind the heel and the two halves have hook portions, which interengage and are locked against a movement at right angles to the plane of the coupling members when the binding is closed and the interengaging surfaces of these hook portions are forced together and are approximately parallel or only slightly inclined to the longitudinal center line, each of the coupling members having a stop, which is spaced from the interengaging surfaces of the hook portions, and these stops being arranged to be forced toward each other by a force acting on one of the cable ends in a lateral direction away from the ski, and to form a fulcrum for a pivotal movement of the coupling members, whereby the hook portions are disengaged. When the binding is being used, the yoke halves are forced against the heel by the cable tension acting in the longitudinal direction of the ski. As a result, the hook portions are particularly firmly interengaged because the heel forces the front hook portion into the recess of the rear hook portion, and the support of the yoke halves against the heel causes the forces acting on the yoke halves in the longitudinal direction of the ski to be deflected and produce laterally directed forces, which promote the interengagement of the hook portions. In response to a lateral displacement of the heel of the boot, the stop faces of the two coupling members are forced against each other, and a further action of a lateral force will result in a pivotal relative movement of the coupling members about the point of contact of the stop faces acting as abutments so that the hook portions are disengaged and the binding entirely releases the foot.

In a particularly simple manner, the means for locking the hook portions against a movement at right angles to the plane of the coupling elements may consist of guide plates, which are connected to one hook portion and engage the side faces thereof and guide the other hook portion. According to another advantageous suggestion of the invention, a detent device is provided for a readily

2

releasable retention of the hook portions in their interengaging position. To this end, at least one of said guide plates may be resiliently connected to the associated hook portion and may be provided with a bulge, which contacts with a detent socket of the other hook portion.

5 Whereas a readily releasable retention of the hook portions in their interengaging position is not required for the function of the coupling device according to the invention, this detent arrangement facilitates substantially the application of the binding cable because the coupling elements would otherwise be retained in their interengaging position only by the tension of the binding cable and the reaction pressure of the heel of the boot and would have to be held together by hand until the cable 10 has been tensioned.

In order to obtain the safety function of the coupling according to the invention also in the case of frontal falls, the rear hook portion, considered in the longitudinal direction of the ski, may be pivoted to the 15 associated coupling member in such a manner that this hook portion will release the other hook portion by a rearward pivotal movement, and the pivoted hook portion may be locked by a locking device, which releases the pivotal movement when a predetermined cable tension 20 is exceeded. As the rear hook portion, considered in the longitudinal direction of the ski, is subjected by means of the front hook portion to the action of the cable tension and of the reaction pressure exerted by the heel of the boot, this rear hook portion will be pivotally moved 25 rearwardly as soon as it can pivotally move relative to the associated coupling member bearing on the heel. As a result, the other hook portion is disengaged from the pivoted hook and the heel of the boot is released.

In a preferred embodiment, the pivoted hook portion 30 may have a stop, which locks the hook portion against a pivotal movement when this stop engages a counterstop arranged on the associated coupling member, whereas the counterstop is displaceable in the coupling member in dependence on the cable tension to such an extent that the stop of the hook portion is released. Each coupling member may have in known manner an abutment surface for a coil spring, which surrounds the rear end of the cable and against which the cable is supported by a spring washer, the counterstop consisting of a slide which is connected to the spring washer of its coupling member. The foot will be released as soon as the respective coil spring has been compressed by the cable tension to such an extent that the slide has been moved out of the path of the 40 pivotal movement of the stop of the associated hook portion. In this connection it is particularly suitable if the position of the slide relative to the spring washer is adjustable so that the releasing moment or, in other words, the spring displacement required for the release, can be individually determined in dependence on the weight of the skier and, if desired, on other circumstances.

In a modification of the embodiment which has just been discussed, the counterstop may be displaceable in the associated coupling member against the force of a return spring under the action of a tension element, which 45 is secured to a binding part which is inelastically connected to the ski, whereas this tension element is movable relative to the resiliently fixed cable. This tension element may consist of a thin wire, a filament of plastics material, or the like, and may be disposed inside the protective 50 sheath of the corresponding cable section, but is directly connected to the front tightener, to which the cable is connected by coil springs. The effective length of the tension element may be adjustable for determining that spring displacement which is required for a release of the coupling members from each other in the case of a frontal fall.

In a further embodiment, the locking device may consist of a detent device, which is effective between the movable hook portion and the associated coupling half and which is adjustable with respect to its retaining pressure.

Various embodiments of the invention will be explained more fully by way of example in the following description with reference to the drawing, in which

FIG. 1 is a side elevation showing a first embodiment of the coupling device according to the invention and

FIG. 2 is a top plan showing the coupling device of FIG. 1, the parts which are covered by the spring plate being indicated in broken lines,

FIG. 3 is a top plan view similar to FIG. 2 and shows the released coupling device,

FIG. 4 shows another embodiment in a top plan view, 15 partly in section,

FIG. 5 shows the embodiment of FIG. 4 with the coupling released by a frontal fall,

FIG. 6 is a sectional view taken on line A-B of FIG. 4,

FIG. 7 a sectional view taken on line C-D of FIG. 4,

FIG. 8 a sectional view taken on line E-F of FIG. 4,

FIG. 9 a top plan view showing another embodiment of the coupling device according to the invention,

FIG. 10 a diagrammatic view showing the associated tightener and the means for spring-connecting the binding cable to this tightener,

FIG. 11 is a side elevation similar to FIG. 8,

FIG. 12 a top plan view showing a final embodiment,

FIG. 13 a side elevation, partly in section, showing the embodiment of FIG. 12, and

FIG. 14 the use of the embodiment of FIGS. 12 and 13 with a short heel cable, which is secured to the side faces of the ski.

As is apparent from FIG. 2, the coupling device according to the invention consists of the coupling members 1 and 2, which form the two parts of a yoke, which engages the heel of the skiing boot 7 at A and B and conforms to the shape of the heel. The cable sections 3 and 10 are secured to the front ends of the coupling sections 1 and 2. The coupling member 1 comprises a hook portion 8 and the coupling member 2 comprises a hook portion 14. When the hook portions 8 and 14 are interengaged, a dropping of the coupling member 1 with the hook portion 8 or an upward movement of the same is prevented by the resilient guide plate 4 (see FIG. 1), which is U-shaped in cross-section and formed with a bulge 5. The spring plate is riveted to the coupling member 2 at 9. The hook portion 8 has a detent socket 6, which is engaged by the bulge 5 when the coupling device is being assembled. This arrangement ensures that the coupling members 1 and 2 will remain connected to each other even when the cable 3, 10 has not yet been tightened, unless the coupling members are pulled apart against the very small retaining force of the detent device 5, 6.

The two coupling members are provided with co-acting stops 13 and 15, which are spaced from the inter-engaging parts of the hooked portions 8 and 14. These stops are arranged to strike on each other when the hook portion 14 of the coupling member 2 is in snug engagement with the recess in the coupling member 1. If the coupling device according to the invention is used with a boot which has a narrower heel than that which is shown, the hook portion 14 will not completely enter the recess in the coupling member 1 and the stop faces 13 and 15 will not contact during the normal use of the binding.

When the cable 3, 10 is tensioned in the direction of the arrows x by means of a front tightener, which is not shown, the support of the yoke halves 1 and 2 at A and B against the heel of the skiing boot 7 will give rise to lateral forces, rather than a forwardly directed tension, in the region in which the hook portions 8 and 14 interengage. By these lateral forces, the interengaging faces of the hook portions will be forced particularly firmly together at C. This effect will also be obtained if the heel of the skiing boot is smaller than that shown in the draw-

ing. In this case the stop faces will not contact during the normal use of the binding but the interengagement of the hook portions 8 and 14 at C will be retained. This interengagement will be obtained regardless of the presence or absence of the detent socket 6 and of the bulge 5 on the spring plate 4. Even when the two coupling members 1 and 2 are very loosely fitted together before the cable 3, 10 is tensioned, a firm connection will be effected by the tension acting in the direction x.

When a twisting fall or another strong lateral stress causes a lateral force in the direction y or y' to act on the heel and on the binding cable 3, 10, and down-pulls 11, 12 are provided, the cable will be torn out of the corresponding down-pull. For this purpose this down-pull must be so designed in known manner that the cable can slip out under a strong lateral force. As is clearly apparent from the drawing, the lateral force causes the stop faces 13 and 15 to be forced together so that they form a fulcrum for the ensuing pivotal relative movement of the coupling members 1, 2, whereby the hook portion 8 of the coupling member 1 is moved out of the recess in the coupling member 2 so that the two coupling members are disengaged. The binding has now entirely released the skiing boot 7 and the danger to the leg has been eliminated. The use of the coupling device according to the invention is particularly advantageous when pivoted front safety jaws are provided because such pivoted jaws may restrain the front portion of the foot during a twisting fall and permit only of a rotation of the foot about an axis which extends 25 approximately through the heel region whereas the heel is still restrained, at least at the beginning of the release movement.

Hence, the surprising mode of operation of the invention resides essentially in that the tension x acting in the longitudinal direction is deflected as a result of the support of the coupling members 1 and 2 at a and b so that lateral forces tending to hold the two hook portions in firm interengagement become effective in the region c during the normal use of the binding, whereas lateral forces acting on the heel will displace the points of support from c to the region d at the stop faces 13 and 15, which will then determine the fulcrum of the two coupling members so that the hook portions 8 and 14 will be positively separated from each other.

In the embodiment shown in FIGS. 4 to 8, the design of the coupling members 1 and 2 is basically the same as in the embodiment just described. The spring plate 4 has been replaced by thicker plates 30 and 31, which are secured to the coupling member 2. The rear hook portion 21, considered in the longitudinal direction of the ski, is rotatably mounted at 24 between the plates 30 and 31 and has at its portion which is in front in the drawing a projecting stop 25, which in the position shown in FIG. 4 engages the counterstop 27 and is locked by the same against rotation. On the other side, the stop 25 engages the edge 26 of the plate 30. In this position, the hook portion 21 is entirely rigidly connected to the coupling member 2. As is shown on the drawing, the counterstop 27 consists of a slide, which has at its rear end an angle plate, by means of which it is vertically adjustable by the screw 28. The cable nipple 29 serving as a spring washer has a tapped bore, which receives the adjusting screw 28 so that the slide 27 follows the movements of the spring washer 29 against the force of the compression spring 22. The spring 22 and the similar spring 23 of the coupling member 1 abut at the end of their protecting sleeves and permit of a limited movement of the heel at right angles to the surface of the ski. By such a movement, the springs 22 and 23 are compressed and the spring washers are moved relative to the coupling members 1 and 2. During this movement, the spring washer 29 will drive the slide 27. In the case of excessively high stresses in the longitudinal direction of the ski, such as occur during a frontal fall, the slide 27 assumes the position shown in FIG. 5. In this position, the slide 27 releases the stop 25 so that

the hook portion 21 is immediately pivotally moved in response to the reaction pressure of the skiing boot acting in the direction x , and the hook portion 8 is released. The spring displacement of the spring 22 required for a release of the hook portion 21 by the slide 27 can be adjusted by means of the adjusting screw 28. This embodiment comprises also means for easily detachably locking the hook portion 8 relative to the plate 30 so that the coupling portions need not be held in their interengaging position by hand when the binding is being applied. During a twisting fall, the coupling device according to FIGS. 4-8 is released in the manner which has already been described with reference to FIGS. 1 to 3. In this case the hook portion 21 remains in the position shown in FIG. 4 whereas the coupling members are pivotally moved about the stop faces 13 and 15 to disengage the hook portions 8 and 21 from each other, as shown in FIG. 5.

In the embodiment shown in FIGS. 9 to 11, the springs of the cable loop are provided in the previously usual manner between the cable and a tension element connected to the front tightener 36 of the ski rather than being disposed behind the heel and connected to the coupling device as in the embodiment just described. In order to ensure nevertheless a release of the coupling device in the case of a frontal fall in dependence on the spring displacement, a rope 34 consisting, e.g., of plastics material, is secured to the tension element, without interposition of the coil springs 37 or 38. The effective length of this rope can be adjusted by means of the adjusting screw 35, which is threaded into screw threads of the tension element. The rope 34 extends in the protective sleeve for the cable 3 into the coupling member 2, in which it is fixed in the slide 32, which is pushed by the compression spring 33 into a position in which the slide locks the previously described stop 25 of the hook portion 21 in its engaged position. An excessive force acting in the direction of the arrow x , e.g. during a frontal fall, will result in a movement of the skiing boot at right angles to the surface of the ski. During this movement, the skiing boot drives the coupling members 1, 2 so that the springs 37, 38 are compressed. The rope 34 cannot follow the movement of the cable sections 3 and 10 in the direction of the arrow x but moves relative to the coupling member 2 in the direction of the arrow y until the rope releases the stop 25 so that the hook portion 21 is released for its rearward pivotal movement. When the coupling device has thus been released, the compression springs 37, 38 and 33 relax and the hook portion 21 is moved to its locked position. The same effect is achieved in the embodiment of FIGS. 4 to 8 by the action of the coil spring 22.

In the embodiment shown in FIGS. 12 and 13, the hook portion 21 is locked relative to the plates 30 and 31 by a ball detent device 40-42, which co-acts with a detent socket 39 in the hook portion 21. When the adjusted moment of resistance of the detent device has been overcome by the moment exerted by the lever arm a on the hook portion 21, the latter will be pivotally moved rearwardly so that the coupling device is released. Owing to the larger stress exerted by the ball detent device, the two plates 30 and 31 are additionally held together by a riveted bolt 43. This embodiment of the coupling device according to the invention may be combined with any of the commercial front tighteners.

FIG. 14 shows another arrangement of the coupling device according to FIGS. 12 and 13. In this embodiment the coupling members 1 and 2 are connected only to short cable lengths 44, which are secured to the ski 46 under the ankle with the aid of ring eyelets 45. This embodiment can only be used in conjunction with front jaws which are applied against the front end of the skiing boot 47 and force the same rearwardly.

The embodiments of the invention in which an exclusive property or privilege is claimed are defined as follows:

1. A coupling device for detachably connecting ends of a cable around the heel of a boot to a ski, in which said cable is attached to the ski in a position forward of the rearmost portion of said heel; said device comprising a pair of coupling members, each attached to a corresponding cable end and each comprising a hook portion, a recess portion and a stop portion, the hook portion of each of said coupling members engaging a corresponding recess portion in the other member in a coupled position to form a yoke extending around said heel, a portion of the engaging surfaces of said hook and recess portions being approximately parallel with respect to the longitudinal axis of said ski, so that tightening of said cable in a longitudinal direction with respect to said ski results in lateral forces acting on said engaging surfaces to strengthen said coupling, each stop portion being spaced from its respective hook and recess portion and being arranged so that when a predetermined lateral force on said boot is exceeded, said stop portions mutually engage to form a fulcrum for pivotable uncoupling movement of said coupling members.
2. The device of claim 1 further comprising means for locking said coupling members in said coupled position from movement in a direction normal to the upper surface of said ski.
3. The device of claim 2 wherein said locking means comprises a pair of guide plates connected to one of said coupling members and extending over said engaging surfaces in said coupled position.
4. The device of claim 1 further comprising means to quickly detachably retain said coupling members in an interengaging position.
5. The device of claim 1 wherein one of said coupling members further comprises uncoupling means to uncouple said coupling members when a predetermined longitudinal force on said boot is exceeded.
6. The device of claim 1 wherein said uncoupling means comprises a connecting member to which one of said coupling members is pivotally mounted to move between a coupled and an uncoupled position with respect to said other coupling member; a stop member slidably mounted in said connecting member and connected to one of said cable ends; and resilient means normally urging said stop member into blocking engagement with said one coupling member to retain same in said coupled position, said resilient means permitting movement of said stop member out of said blocking engagement in response to a predetermined longitudinal force on said boot being exceeded transmitted via the cable, thus permitting the pivotable movement of said one coupling member to the uncoupled position.
7. The device of claim 6 further comprising means to regulate the amount of said predetermined longitudinal force required to urge said stop member out of said blocking engagement.
8. The device of claim 5 wherein said uncoupling means comprises a connecting member to which one of said coupling members is pivotally mounted to move between a coupled and an uncoupled position with respect to said other coupling member, a pair of guide plates connected to said connecting member and extending over said engaging surfaces in said coupled position, a detent member extending through one of said guide plates and into a socket provided in said one coupling member in said coupled position, and adjustable resilient means urging said detent member into said socket in said coupled position, said resilient means permitting movement of said one coupling member out of engagement with said detent member in response to a predetermined longitudinal force on said boot being exceeded transmitted by the cable, thus permitting the pivotable movement of said one coupling member to the uncoupled position.
9. A coupling device for detachably connecting ends of a cable around the heel of a boot to a ski in a position

forward of the rearmost portion of said heel, said device comprising a pair of coupling members, each of which comprise a hook portion, a recess portion and stop portion, the hook portion of each of said coupling members engaging a corresponding recess portion in a coupled position to form a yoke extending around said heel, one of said coupling members being connected to one of said cable ends; a connecting member to which the other of said coupling members is pivotally mounted to move between a coupled and an uncoupled position with respect to said one coupling member; stop member slidably mounted in said connecting member and connected to another of said cable ends; and resilient means normally urging said stop member into blocking engagement with said other coupling member to retain same in said coupled position, said resilient means permitting movement of said stop member out of said blocking engagement in response to a predetermined longitudinal force on said boot being exceeded transmitted via the cable, thus permitting the pivotable movement of said other coupling member to the uncoupled position.

10. The device of claim 9 further comprising means for locking said coupling members in said coupled position from movement in a direction normal to the upper surface of said ski.

11. The device of claim 10 wherein said locking means comprises a pair of guide plates connected to one of said coupling members and extending over said engaging portions in said coupled position.

12. The device of claim 9 further comprising means to quickly detachably retain said coupling members in an inter-engaging position.

13. The device of claim 9 further comprising means to regulate the amount of said predetermined longitudinal force required to urge said stop member out of said blocking engagement.

14. A coupling device for detachable connecting ends of a cable around the heel of a boot to a ski in a position forward of the rearmost portion of said heel, said device comprising a pair of coupling members, each of which comprise a hook portion, a recess portion and stop portion, the hook portion of each of said coupling

5 members engaging a corresponding recess portion in a coupled position to form a yoke extending around said heel, one of said coupling members being connected to one of said cable ends; a connecting member to which the other of said coupling members is pivotally mounted to move between a coupled and an uncoupled position with respect to said one coupling member; another of said cable ends being connected to said connecting member; a pair of guide plates connected to said connecting member and extending over said engaging surfaces in said coupled position, a detent member extending through one of said guide plates and into a socket provided in said other coupling member in said coupled position, and resilient means urging said detent member into said socket in said coupled position, said resilient means permitting movement of said other coupling member out of engagement with said detent member in response to a predetermined longitudinal force on said boot being exceeded transmitted by the cable, thus permitting the pivotable movement of said other coupling member to the uncoupled position.

15. The device of claim 14 further comprising means to regulate the amount of said predetermined longitudinal force required to move said other coupling member out of engagement with said detent member.
